ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

ART OF MAKING SHOES.

1,159,083.

Specification of Letters Patent.

Patented Nov. 2, 1915.

Application filed November 16, 1912. Serial No. 731,894.

To all whom it may concern:

Be it known that I, ADAM H. PRENZEL, citizen of the United States, residing at Halifax, in the county of Dauphin and State of Pennsylvania, have invented certain new and useful Improvements in the Art of Making Shoes, of which the following is a specification, reference being had therein to the accompanying drawing.

This invention relates to an improvement in the art of making shoes, and more particularly in making shoes of that type in which the upper is provided with an outwardly turned portion which is adapted to be secured to the outer sole, and an object of the present invention is the provision of a simple and efficient method for making shoes of this character whereby the shoes will compare favorably in appearance with shoes of the well known welt or turned types and which can be practised much more economically and easily than the methods now employed for making shoes of these types.

The novel shoe herein disclosed is not claimed herein but is claimed in my co-pending application Serial No. 731,892, filed of even date herewith, while similarly the novel shoe sole produced in the practice of the process of the present invention is not claimed herein but is claimed in my co-pending application Serial No. 731,893, also filed of even date herewith.

In the drawings, wherein is illustrated a convenient embodiment of a shoe made according to the present method, and wherein like characters of reference refer to similar parts in the several views, Figure 1 is a top plan view of an unfinished shoe, embodying the present invention; Fig. 2 is an elevation of the completed shoe; Fig. 3 is a bottom plan of one end part of the shoe showing a portion of the insole, Fig. 4 is a bottom plan of the insole; Fig. 5 is a plan of the outsole; Fig. 6 is a cross section of the outsole; Fig. 7 is a cross section of the insole, and Fig. 8 is an enlarged sectional view showing the various parts in their connected association when the shoe is completed.

Referring now more particularly to the drawings, the shoe as made according to the present method comprises an upper A, an outer sole B, and an inner sole C.

In carrying out the present method, a

strip of material is removed from the upper surface of the outer sole B so as to provide a channel b around the edge of the front portion thereof, the ends of which terminate adjacent the heel portion of the sole. In forming the channel b in the outer sole, the material is so cut that said channel will be provided with an abrupt or substantially vertical inner shoulder b', and the bottom surface thereof will be inclined downwardly from the inner edge to the outer edge of the channel. Cutting the outer sole in this manner also provides a strip which is removed from the outer sole with a transversely inclined under surface, said strip being fixed at its outer portion. The strip which is removed from the sole B to form the channel b therein is severed from the sole at one end only so that there is provided, a welt strip F which is integral with the sole and is connected thereto at one end only. Simultaneously with the removal of the strip F from the outer sole B, a portion of the outer edge of said strip is cut away, so that the welt strip will be of slightly less width than the channel b in the outer sole, for a purpose to be hereinafter more particularly set forth. With the outer sole prepared in this manner, an inner sole C is positioned thereover, which is of such a size that when superposed on the outer sole, the outer portion thereof will project outwardly beyond the shoulder b' of the channel or recess in the outer edge of the outer sole and will overlie the base or bottom of such channel or recess. The sides of the inner sole C have secured thereto in any suitable manner, flaps or welts c c of fabric or other strong flexible material, such flaps or welts extending conveniently from the shank on the inner sole to points adjacent to the front thereof.

The upper A of the shoe, which may be of any suitable form, is provided with short inwardly extending cuts a a in its lower edge on each side thereof, which are adapted, when the upper is positioned over the outer sole, to overlie the end portions of the channel or recess b therein. To secure the upper in position, the lower edge thereof, forward of the cuts a a therein, is turned outwardly as at a', and the upper is positioned on the outer sole so that the outwardly turned portion a' thereof will be positioned within the channel b in the outer

sole and will also overlie the flaps or welts *c c* of the inner sole. With the parts in this position, the outwardly turned portion *a'* of the upper and the portions of the flaps or welts *c c* of the inner sole positioned therebeneath, are tucked inwardly into the space which is provided between the outer portion of the inner sole and the base of the channel *b* which is formed in the outer edge 5 of the outer sole, so that a portion of the upper will directly overlie the abrupt or vertical shoulder *b'* of the channel or recess *b* in the outer sole, while the remainder of said outwardly turned portion *a'* of the 10 upper will rest directly upon the bottom of said channel or recess. The tucked-in part of the upper is then secured directly to the outer sole by means of a row of lasting staples or other fastening means *E* which 15 pass through the lower edge of the upper and into the vertical shoulder *b'* of the channel or recess which is formed in the outer edge of the outer sole. This shoulder provides a solid backing against which the 20 lower edge of the upper may be secured by the lasting staples *E*, which staples are allowed to remain in position and become a permanent part of the sole attaching means. The lasting staples *E* which are utilized to 25 connect the upper to the outer sole also pass through the strips of fabric or welts *c c* which are secured to the sides of the inner sole so that said staples or other fastening means serve to connect the inner sole to the 30 outer sole in a strong durable manner so as to practically preclude its separation therefrom.

The lower edge of that portion of the upper in rear of the cuts *a a* is turned inwardly and secured by nails or other suitable fastening means to the underside of the inner sole *C*. The outwardly turned portion *a'* of the upper which overlies the bottom of the channel or recess *b* in the 40 outer sole *B* is next trimmed so that the edge thereof will be positioned inwardly of the edge of the outer sole, and a portion of the bottom of the channel or recess *b* of the outer sole will be exposed. The welt strip 45 *F* formed by the material cut out from the outer sole *B* is then progressively laid upon the outwardly turned portion *a'* of the upper in the channel *b* of the inner sole, beginning at the attached end, the inner edge 50 of said welt strip being forced inwardly between the portion of the upper which is tucked in between the inner and outer soles so as to directly overlie the lasting staples *E* which pass through the upper into the 55 shoulder *b'* of the channel or recess *b* in the inner sole and thus serve to prevent the withdrawal of said staples. With the welt strip *F* in this position, it is secured to the 60 outer edge of the outer sole by a row of stitching *f* or other fastening means which 65

passes through the welt strip, the outer sole, and the interposed portion of the upper, as well as those portions of the flaps or welts *c c* of the inner sole which overlie the base of the channel or recess *b* in the outer sole. 70

The welt strip *F* is of such a width that when secured in position, in the manner just described, the outer edge thereof will lie flush with the outer edge of the sole. This result is obtained by reason of the narrowing of the welt strip when the same is formed, the amount of material which is removed from the outer edge thereof being just sufficient to provide for the thickness of the upper which overlies the shoulder *b'* at 75 the inner edge of the channel or recess *b* of the outer sole *B*. When the welt strip is secured in position, it is drawn tightly into engagement with the exposed portion of the bottom of the channel or recess *b* in the 80 outer sole *B*, so that the joint between the welt strip and the outer sole will be practically invisible and the edge of the upper 85 will not be exposed.

As has been before stated, the welt strip 90 *F* is cut from the outer sole *B* in such a manner as to provide a beveled under surface for the welt strip. As this construction provides the welt strip with an inner edge 95 which is thinner than the outer edge thereof, it facilitates the forcing of the welt strip inwardly between the inner and outer soles. This construction also prevents the formation of a sole of a bulky appearance when the welt strip is secured thereto with the 100 outer edge thereof flush with the outer edge of said sole, since the portion of the welt strip which is removed to provide space for the accommodation of the out-turned portion of the upper, is the thickest portion of 105 the said strip.

In completing the shoe, the heel portion of the outer sole is fastened to the inner sole in any well known manner, and if desired, any well known form of heel may be 110 secured to the outer sole. In the drawings, a spring heel shoe is illustrated, and when the invention is utilized in connection with a shoe of this type, the heel portion of the outer sole is preferably stamped outwardly 115 to form the heel of the shoe, and a filler of any suitable kind is interposed between said stamped-out portion and the heel part of the inner sole, the parts being fastened together 120 in any well known manner.

With a shoe formed by the method above described, it will be seen that as the inner sole projects outwardly beyond the inner shoulder of the channel or recess in the outer sole, and that as such inner sole is secured to the outer sole by the fastening means which are utilized to secure the upper to the outer sole, the upper cannot be drawn inwardly to expose the joint at the inner edge of the welt, and the finished shoe 125 130

does not materially differ in appearance from the ordinary welt and turned shoes as at present manufactured. At the same time the simplicity of the present method and 5 the small number of operations entailed in practising the same renders it possible to manufacture shoes much more economically than can be done by the process at present employed for manufacturing welt and 10 turned shoes.

I claim:—

1. The improvement in the art of making shoes comprising cutting the upper surface of a sole to form along the outer edge thereof 15 of a channel having an inner shoulder, severing the material cut out from the outer sole at one end only to provide a welt strip integral with the outer sole, positioning an upper having an outwardly turned lower edge in the channel of the outer sole, and progressively laying and securing the welt strip in said channel over the outwardly turned portion of the upper.

2. The improvement in the art of making 25 shoes comprising cutting the upper surface of an outer sole to form along the outer edge thereof a channel having an inner shoulder, severing the material cut out from said outer sole at one end of the channel thus formed 30 to provide a welt strip integral with the outer sole, cutting away a portion of said welt strip to reduce the width thereof, positioning an upper with an outwardly turned lower edge in the channel of the outer sole, 35 and securing the welt strip in the channel of the outer sole over the outwardly turned portion of the upper.

3. The improvement in the art of making 40 shoes comprising cutting the upper surface of an outer sole to provide a channel having an inner shoulder and a bottom portion

inclined downwardly from the inner to the outer edge thereof, severing the strip thus cut from the outer sole at one end of the channel only to provide a welt strip integral with the outer sole, cutting away a part from the outer edge of said welt strip to reduce the width thereof, positioning an upper having an outwardly turned lower edge upon the outer sole, and securing the 50 welt strip in the channel of the outer sole over the outwardly turned portion of the upper.

4. The improvement in the art of making 55 shoes comprising cutting an outer sole to provide a channel around the outer edge thereof having an inner shoulder, severing the material cut from the outer sole at one end of said channel only to provide a welt strip integral with the outer sole, position- 60 ing upon the outer sole an inner sole, the outer edge of which projects outwardly be- 65 yond the shoulder of the channel in the outer sole, positioning an upper having an outwardly turned lower edge in the channel 70 of the outer sole, tucking a portion of the upper between the outer edges of the inner and outer soles, securing the tucked-in por- 75 tion of the upper to the shoulder of the channel in the outer sole, positioning the welt strip over the outwardly turned portion of the upper in the channel in the outer sole, and with its inner edge between the inner and outer soles, and connecting the welt strip, outer sole and interposed portion of the upper.

In testimony whereof I affix my signature in presence of two witnesses.

ADAM H. PRENZEL.
